UNITED STATES PATENT OFFICE.

ALBERT H. STEBBINS, OF LOS ANGELES, CALIFORNIA.

CLASSIFIER.

Application filed December 15, 1926. Serial No. 154,879.

This invention relates to classifiers of the type in which materials passing downwardly within a treatment chamber under the influence of gravity are subjected to the action 5 of air currents that separate the finer particles from the coarser materials.

In employing classifiers of this general type it is difficult to effect a complete separation of the materials through the use of 10 an air blast alone, or through an air exhaust alone, and if the materials being treated are relatively fine it will be necessary to subject them repeatedly to the action of separating air currents in order to remove completely 15 the finer particles from the slightly larger particles.

The present invention is therefore directed to a multiple treatment classifier which is so constructed that as the materials pass downwardly within the treatment chamber they are subjected time and time again to separating air currents which gradually remove the finer particles from the slightly larger 20 particles.

One important feature of the present invention resides in the novel construction of the treatment chamber and in the arrangement of parts whereby air jets are provided within the treatment chamber at a number 25 of points throughout its length, and also in the construction whereby air is exhausted from the treatment chamber at different points throughout its length.

Another feature of the invention resides 30 in the arrangement of partitions within the treatment chamber to divide the same into a number of settling compartments.

Another feature of the invention resides 35 in means for introducing air from the atmosphere into the casing adjacent the lower ends 40 of the partitions.

Still another feature of the invention resides in a novel type of closure for regulating the flow of materials from the feed hopper to the treatment chamber.

Other features of the invention and novel combination of parts in addition to the above will be hereinafter described in connection with the accompanying drawings which illustrate 45 one good practical form of the invention.

In the drawings:—

Fig. 1 is a vertical sectional view through a classifier constructed in accordance with 50 the present invention;

Fig. 2 is a top plan view of Fig. 1;

Fig. 3 is a sectional view taken on the line 3—3 of Fig. 1;

Fig. 4 is a vertical sectional view of the lower portion of the classifier of Fig. 1, 60 the shaded lines being omitted and the section is taken so as not to cut the air inlet passages in the outer wall; and

Fig. 5 on an enlarged scale is a sectional view on the line 5—5 of Fig. 4. 65

In the embodiment of the invention illustrated the classifier is shown as cylindrical in shape and as having a casing 10 in which treatment of the materials is effected. About the casing 10 is provided an outer casing 11 that is supported in spaced relation to the casing 10 to form the air exhaust passage 12 between the two casings. The upper portion of the passage 12 flares outwardly somewhat as at 13 to form an annular space 14 of increased area. Air is exhausted from the annular space 14 by a suction pipe 15 that leads to the suction fan 16. 70

Within the casing 10 are provided a series of partitions 17 which serve to divide the 80 treatment chamber into a number of settling compartments. These partitions are shown as frusto-conical in shape and are supported one above the other in nested relation and the inclined walls of the partitions slope 85 downwardly in a direction to direct the materials that settle upon the walls toward the central opening 18 at the lower end of each frusto conical partition. The upper ends of the partitions 17 preferably fit snugly within the casing 10 and may be riveted or otherwise secured to the wall 10. 90

The classifier of the present invention is supported in an upright position as shown so that the materials to be treated will pass 95 downwardly within the treatment chamber under the influence of gravity. The total length of the classifier and the number of partitions mounted within the treatment chamber will depend largely upon the nature 100 of the materials being treated. If the materials being treated are relatively coarse then a few air treatments will serve to effect the desired separation, but if the classifier is designed to separate fine dust-like materials then a large number of treatments will be necessary to completely remove the finer particles from the slightly coarser particles, in which case a large number of partitions 105 17 should be provided.

In the embodiment of the invention shown, the materials are delivered to the

upper portion of the classifier by a hopper 19 which may be mounted within the cylindrical casing 10. The flow of materials from the lower end of the hopper into the treatment chamber is controlled by a closure or adjustable head 20 which is shown as mounted upon the centrally disposed air blast pipe 21. The upper portion of the closure 20 is conical in shape and is provided with the air apertures 22 through which air may escape into the hopper 19 to prevent the materials from clogging at the discharge end of the hopper. Air under pressure is delivered to the interior of the closure 20 by providing the air discharge openings 23 in the side walls of the air blast pipe 21. The rate at which the materials are delivered to the treatment chamber by the hopper may be regulated by moving the closure 20 lengthwise of the air blast pipe towards and from the discharge end of the hopper, and the closure may be secured in the desired position of adjustment by tightening the clamping means 24 provided at the upper end of the closure to embrace the pipe 21.

The frusto-conical partitions 17 are supported in spaced relation to each other to form the settling compartments or chambers 25 between them, as best shown in Fig. 4.

Air under pressure is supplied to the air blast pipe 21 by the horizontally extending pipe 26 which leads from the blast fan 27, and the amount of air supplied to the blast pipe 21 may be controlled by adjusting the sliding gate 28. The pipe 21 is mounted centrally within the casing 10 and extends downwardly through the openings 18 of the various partitions 17, and this pipe is provided at various points along its length with the air discharge openings 29. These openings are so positioned that as the materials passing downwardly within the classifier escape from the discharge end 18 of one frusto-conical partition they will be carried outwardly and upwardly by the air blast into the next settling compartment 25. In this manner the materials are treated time and time again as they pass downwardly within the treatment chamber. The air jets employed to carry the materials into the settling compartments 25 should be directed upwardly to some extent, and to this end an annular flange or the like 30 may be provided immediately below each group of openings 29 to direct the air currents upwardly slightly, as indicated by the arrows. The diameter of the air blast pipe 21 may be gradually decreased towards the lower end of the casing, as will be apparent from the drawing, and the lower end of this pipe may be provided with a discharge spout 31 through which the pipe may be blown out from time to time, but which spout is normally closed by the gate or valve 32.

The lighter materials which remain sus-

pended within the air in the settling compartments 25 are preferably exhausted from the upper end of these compartments, and this is accomplished in the embodiment of the invention shown by providing the passages 33 which lead from the upper portion of the settling compartments 25 to the air exhaust chamber 12, the arrangement being such that the air is drawn upwardly within the compartments 25 through the openings 33 into the suction chamber 12 by the exhaust fan 16. The amount of air exhausted from the suction chamber 12 by the fan 16 may be controlled by adjusting the sliding gate 34.

It will be understood that the heavier particles that settle within the compartments 25 slide downwardly along the inclined walls of such compartments into the path of the next set of air jets 29, to be carried upwardly into another settling compartment for further treatment. The heavier materials that pass through the entire series of frusto-conical partitions will collect in the hopper 35 at the lower end of the classifier and from which they may be withdrawn from time to time by opening the discharge gate 36.

It will be apparent from the foregoing that the volume of air exhausted from the treatment chamber may be controlled by adjusting the gate 34, and that the amount of air delivered to the treatment chamber by the air blast pipe 21 may be controlled by adjusting the gate 28. If the volume of air removed from the treatment chamber should exceed the amount of air delivered thereto, there would be a tendency to create a vacuum within the treatment chamber which would effect the separating operation. In order to prevent the formation of such partial vacuum within the classifier it may be desirable to introduce air from the atmosphere into the treatment chamber. This is accomplished, in accordance with the present invention, by arranging certain of the conical partitions 17 so that the air inlet passages 37 are formed between them and air from the atmosphere is admitted to these passages by providing the air inlet ports 38 formed through the inner and outer casings 10 and 11. The amount of air admitted to the treatment chamber through the ports 38 may be controlled by adjusting the gates 39 mounted upon the outer casing 11 to cover the outer ends of the ports 38. The arrangement just described is such that the air introduced from the atmosphere will move downwardly within the space 37 between adjacent partitions and will flow upwardly around the lower end of a partition into a settling compartment 25. This arrangement has the advantage that the air from the atmosphere passing upwardly around the lower end of a frusto-conical

partition 17 will help to carry upwardly into the adjacent settling compartment the finer particles traveling downwardly along the inclined walls of the partition.

- 5 By adjusting the gates 28 and 34 to control the strength of the air blast and the strength of the air exhaust means as above described, and by adjusting the sliding gates 39 which regulate the flow of air from the 10 atmosphere into the treatment chamber, the separation of the materials within the classifier may be accurately controlled, and since the materials passing downwardly within the classifier are subjected time and time again 15 to the separating action of the rising air currents, a thorough separation of the materials may be secured. The particles which settle within the air exhaust passage 12 will move downwardly into the discharge hopper 20 40 from which they may be drawn from time to time by opening the discharge gate 41.

What is claimed is:

1. A classifier comprising in combination, an upright casing, means for delivering the 25 materials to be treated to the upper portion of the casing to pass downwardly within the central portion of the casing, frusto-conical partitions supported one above the other about the central axis of the casing to 30 form downwardly inclined settling chambers between them and the partitions being constructed to direct the particles sliding down their inclined walls toward said central axis, means for producing air jets within the casing 35 for blowing the falling materials outwardly into the settling chambers, and means for removing from the settling chambers the lighter particles that remain suspended in the air.
- 40 2. A classifier comprising in combination, an upright casing, an air blast pipe mounted centrally within the casing and having air discharge openings provided at intervals along the pipe, means for delivering the materials to be treated into the upper portion 45 of the casing to pass downwardly therein, frusto-conical partitions surrounding said pipe and arranged in spaced relation to each other to form settling chambers between 50 them and constructed so that the materials that settle upon the inclined walls of the partitions will slide down these walls toward said pipe and into the path of the air blast, and means for removing from the settling 55 chambers the lighter particles that remain suspended in the air.

- 60 3. A classifier comprising in combination, an upright casing constructed to form a treatment chamber, means for delivering the materials to be treated to the upper portion of the casing to pass downwardly within the central portion of the casing, frusto-conical partitions supported one above the other within the casing in spaced relation to form 65 settling chambers between them and con-

structed to direct the particles that settle upon the inclined walls of the partitions toward the central axis of the treatment chamber, means for removing from the settling chambers the lighter particles that remain suspended in the air, and means forming air inlet passages for conducting air from the atmosphere into the casing around the lower edge of the conical partitions.

4. A classifier comprising in combination, 75 an upright casing constructed to form a treatment chamber, means for delivering the materials to be treated to the upper portion of the casing to pass downwardly within the central portion of the casing, frusto-conical partitions supported one above the other within the casing in spaced relation to form settling chambers between them and constructed to direct the particles that settle upon the inclined walls of the partitions 80 toward the central axis of the treatment chamber, means for removing from the settling chambers the lighter particles that remain suspended in the air, means forming air inlet passages for conducting air from 85 the atmosphere into the casing around the lower edge of the conical partitions, and adjustable means for regulating the amount of air admitted to the casing from the atmosphere.

5. A classifier comprising in combination, 95 an upright casing, means for delivering the materials to be treated to the upper portion of the casing to pass downwardly therein, 100 frusto-conical partitions supported one above the other in the casing to form settling chambers between them and provided with central openings through which the materials are directed by the inclined walls of the partitions, a blast pipe mounted centrally 105 within the casing and provided with apertures at intervals along its length for directing air currents against the falling materials to carry the materials upwardly into the settling chambers, and means for exhausting air from the upper portion of the settling 110 chambers.

6. A classifier comprising in combination, 115 an upright casing, an air blast pipe mounted centrally within the casing, means for delivering the materials to be treated to the upper portion of the casing to pass downwardly therein adjacent said pipe, partitions mounted in the casing in spaced relation to each other to form settling chambers between 120 them and having inclined walls for directing the materials that settle upon the partitions toward said pipe, and said pipe being provided with air blast openings through which air is directed against the falling materials 125 to carry them into the settling chambers.

7. A classifier comprising in combination, 130 an upright casing, an air blast pipe mounted centrally within the casing, means for delivering the materials to be treated to the

upper portion of the casing to pass downwardly therein adjacent said pipe, partitions mounted in the casing in spaced relation to each other to form settling chambers between them and having inclined walls for directing the materials that settle in the chambers toward said pipe, means for exhausting air from the settling chambers, and the air blast pipe being provided with air blast openings through which air is directed against the falling material to carry them into the settling chambers.

8. A classifier comprising in combination, an upright casing having formed therein a treatment chamber, means for delivering the materials to be treated to the upper part of said casing to pass downwardly therein, partitions mounted in the casing in spaced relation to each other to form settling chambers between them and having inclined walls for directing the materials that settle in the chambers toward the central axis of the casing, means for directing jets of air against the materials moving downwardly within the casing to carry them into the settling chambers, and means surrounding said casing for exhausting air from the settling chambers.

9. A classifier comprising in combination, an upright casing having a treatment chamber, an outer wall surrounding said casing and forming an air exhaust chamber surrounding said casing, inclined partitions mounted in the casing in spaced relation to each other to form settling chambers between them, means for delivering the materials to be treated into the upper portion of said casing to move downwardly therein, means forming a communication between said exhaust chamber and the settling chambers and means for exhausting air from the exhaust chamber to carry off the lighter materials within the casing.

10. A classifier comprising in combination, an upright casing having a treatment chamber, an outer wall surrounding said casing and forming an air exhaust chamber surrounding said casing, inclined partitions mounted in the casing in spaced relation to each other to form settling chambers between them, means for delivering the materials to be treated into the upper portion of the casing to pass downwardly therein, means forming an air passage between said exhaust chamber and the settling chambers to effect the removal of the lighter particles that remain suspended in the air from the settling chambers, and air inlet ports formed through said outer wall for admitting air from the atmosphere into the interior of said casing.

11. A classifier comprising in combination, an upright casing, a series of frusto-conical partitions mounted in the casing in nested

relation and arranged to form settling chambers between some of the partitions and air inlet chambers between other partitions and through which air is conducted downwardly to the lower ends of the partitions, means for delivering the materials to be treated into the upper portion of the casing to move downwardly therein through central openings in the partitions, means for introducing air from the atmosphere into the casing between certain partitions, and means for exhausting air from said settling chambers.

12. A classifier comprising in combination, an upright casing, an air blast pipe mounted within the casing, inclined partitions mounted in the casing in spaced relation to each other to form settling chambers between them and provided with downwardly sloping walls that direct the materials toward said pipe, a feed hopper surrounding said pipe, and an annular closure for the lower end of the feed hopper adjustably mounted upon said pipe and movable lengthwise of the pipe to vary the size of the feed opening.

13. A classifier comprising in combination, an upright casing, an air blast pipe mounted within the casing, inclined partitions mounted in the casing in spaced relation to each other to form settling chambers between them and provided with downwardly sloping walls that direct the materials toward said pipe, a feed hopper for delivering materials to the casing, a closure for the lower end of the feed hopper and constructed to surround said pipe and provided with air discharge apertures, and means for introducing air into the closure from said pipe to produce air jets through said apertures to promote feeding of the materials.

14. A classifier comprising in combination, an upright casing, means for delivering the materials to be treated to the upper portion of the casing to pass downwardly therein under the influence of gravity, a series of frusto-conical partitions mounted one above the other in nested relation to form downwardly inclined settling chambers between them and which are shaped to direct the materials moving downwardly within the chambers toward the central axis of the casing, an annular wall provided at the upper end of each partition and arranged to provide a narrow annular slot at the upper end of each settling chamber, means for exhausting air from the settling chambers through said narrow slots, and means for blowing the materials moving downwardly within the casing outwardly into the settling chambers.

In testimony whereof, I have signed my name to this specification.

ALBERT H. STEBBINS,
